ATTORNEY.

UNITED STATES PATENT OFFICE.

GEORGE E. POTTER, OF PALMER, MASSACHUSETTS.

SHUTTER-WORKER.

SPECIFICATION forming part of Letters Patent No. 319,999, dated June 16, 1885.

Application filed May 26, 1885. (No model.)

1884

To all whom it may concern:

Be it known that I, GEORGE E. POTTER, a citizen of the United States, residing at Palmer, in the county of Hampden and State of Massachusetts, have invented new and useful Improvements in Blind-Operating Apparatus, of which the following is a specification.

This invention relates to improvements in window-blind-operating devices adapted to be operated from the interior of a building, the object being to improve the details of the construction of such apparatus, as hereininafter set forth.

In the drawings forming part of this specification, Figure 1 is a plan view representing, partly in section, a portion of a building at the corner of a window, and a part of a blind hinged thereto, and having connected with the latter blind-operating devices embodying my invention. Fig. 2 is a similar view to Fig. 1, but showing the position of the operating devices when the blind is opened. Fig. 3 is a side elevation, partly in section, of a portion of a building inside of and near the window.

In the drawings, A is a part of the wall of a building. D is the inside casing. B is the window-jamb. B² is the window-seat. b is the window-blind, and c is the blind-hinge.

The letters a and a² indicate the positions of the window-sashes.

The window-blind b is hung in the ordinary way by two hinges, the lower one of which, c, is shown in the drawings.

To operate the blind b from within the house, the following-described devices are employed: A metallic or other suitable bar, d², having a handle, d', thereon, is inserted in a passage through the wall of the building and one leaf of hinge c, or a suitable metal guide-plate. A metallic washer, o, surrounds said passage on the inside casing, D. A short bar, d²⁰, is hinged to the end of bar d² at f, one side of which is provided with serrations w, and a third bar, d, having one side thereof serrated to match bar d²⁰, and having a slot in it at said serrated portion, is secured to bar d²⁰ by a screw, m, which passes through said slot and into the last-named bar. The bar d² is

provided with notches v on its under side, of proper width to engage with the edge of the washer o, and bar d has a curved projection, x, on one side of it, which, when the said bars are in the position shown in Fig. 1, is adapted to bear against one side of the opening in the plate of hinge c, through which bar d passes.

The above-described handled-bar construction constitutes practically a single bar adapted to have a sliding movement in the passage through the wall of the house. Said bar is jointed at f, in order that the handled end thereof may be dropped down parallel with the inner wall, as shown in Fig. 3, to lock the blind open. The lapped and serrated portions d and d²⁰ provide means whereby, by the aid of screw m, the bar may be elongated or shortened to adjust it to walls of different thicknesses. The notches v in the part d² provide means for securing the bar in different positions by engaging the notches with the edge of the washer o, and thereby swinging and holding the blind more or less open.

The curved projection x on the side of the bar d serves to make the latter more rigid when the blind is shut, by causing the bar to bind in the opening in the plate of the hinge c through which it passes.

Between the outer end of the bar d and the blind c are secured three lever-bars, e e e, one being secured by one end thereof to the blind by the bolt e', and the two others pivoted together and to the last-named one and to the end of said bar d.

Bar d and the two succeeding lever-bars e have inclined shoulders 5 formed thereon a little back of their pivots, against which the adjacent edges of the bars e are brought to bear when the handle-bar is moved to open and shut the blind, and whereby the latter is made to swing. When the blind is open, the said two intermediate lever-bars enter within the passage in the wall, as shown in Fig. 2.

When the within-described devices are used on heavy shutters, the wheel 55 (shown in full in Fig. 2 and in dotted lines in Fig. 1) may be hung on the hinge-pin, and when bar d is operated to open the shutter the lever-bars e

are supported by the border of said wheel against any lateral movement which too great strain might cause.

What I claim as my invention is—

5 The handle-bar consisting of the bar d^2 and the bar d^{20} , hinged together, and the bar d , adjustably attached to the latter, whereby the

length of the handle-bar may be varied, the lever-bars e , and blind e , combined and operating substantially as set forth.

GEO. E. POTTER.

Witnesses:

H. A. CHAPIN,
J. D. GARFIELD.

It is hereby certified that the date of filing of the application for Letters Patent No. 319,999, granted June 16, 1885, to George E. Potter, of Palmer, Massachusetts, for an improvement in "Shutter-Workers," was erroneously printed at the head of the specification as "May 26, 1885"; that said date should have been printed *May 26, 1884*; and that the said Letters Patent should be read with this correction therein that the same may conform to the record of the case in the Patent Office.

Signed, countersigned, and sealed this 22d day of September, A. D. 1885.

[SEAL.]

H. L. MULDROW,

Acting Secretary of the Interior.

Countersigned:

M. V. MONTGOMERY,
Commissioner of Patents.
